(57) **CLAIM**

The ornamental design for a center beam high bay edgelit luminaire, as shown and described.

DESCRIPTION

FIG. 1 is a bottom perspective view of a center beam high bay edgelit luminaire, showing our new design;

FIG. 2 is a top perspective view thereof;

FIG. 3 is a bottom plan view thereof;

FIG. 4 is a top plan view thereof;

FIG. 5 is a left-side elevation view thereof;

FIG. 6 is a right-side elevation view thereof;

FIG. 7 is a front elevation view thereof; and

FIG. 8 is a rear elevation view thereof;

FIG. 9 is a bottom perspective view of another embodiment of a center beam high bay edgelit luminaire, showing our new design;

FIG. 10 is a top perspective view thereof;

FIG. 11 is a bottom plan view thereof;

FIG. 12 is a top plan view thereof;

FIG. 13 is a left-side elevation view thereof;

FIG. 14 is a right-side elevation view thereof;

FIG. 15 is a front elevation view thereof; and,

FIG. 16 is a rear elevation view thereof.

The broken lines shown represent unclaimed subject matter and form no part of the claimed design.
